UNITED STATES PATENT OFFICE.

MAGNUS E. WIDELL, OF MAYWOOD, AND ARTHUR A. JAHR, OF FOREST PARK, ILLINOIS, ASSIGNORS TO AMERICAN CAN COMPANY, OF NEW YORK, N. Y., A CORPORATION OF NEW JERSEY.

END FEED FOR DOUBLE SEAMERS.

Application filed November 17, 1920. Serial No. 424,696.

To all whom it may concern:

Be it known that we, MAGNUS E. WIDELL and ARTHUR A. JAHR, citizens of the United States, residing in Maywood and Forest Park, respectively, in the county of Cook and State of Illinois, have invented a new and useful Improvement in End Feeds for Double Seamers, of which the following is a specification.

10 This invention relates in general to can end feeding mechanisms, and while the apparatus herein described is that used as a part of a double seaming machine, it will be understood that the invention contemplates 15 other and different uses and is adaptable to various types of machines in which can ends are separately fed.

A principal object of the invention is the provision of a feeding mechanism of highly 20 efficient and wholly automatic action, which is adapted to separate the can ends from a stack and move them to position to be attached to the can bodies.

Another highly important object of the 25 invention is the provision of means for separating can ends from a stack, adapted to yield in the event of coming directly into contact with the edges of the can ends and having a plurality of operative strokes insuring entrance of said means between the 30 bottommost end and the one next above it, whereby to release said bottommost end.

A further important object of the invention 35 is the provision of a feeding mechanism of this type, which, by slight adjustment of parts, is adapted to handle can ends of different sizes and shapes.

A still further object of the invention is 40 the provision of a mechanism of this kind which is of relatively simple construction and operation and is devoid of delicate parts likely to require frequent repair or replacement.

Other objects and advantages of the 45 invention will be apparent as it is better understood from the following description when considered in connection with the accompanying drawings illustrating a preferred embodiment thereof.

50 Referring to the drawings:

Figure 1 is a side elevation of a can end

feeding apparatus embodying our invention;

Fig. 2 is an enlarged detail of the feeding mechanism taken substantially on the line 55 2-2 in Fig. 1;

Fig. 3 is an enlarged section taken substantially on the line 3-3 in Fig. 1;

Fig. 4 is a section taken substantially on the line 4-4 in Fig. 3;

Fig. 5 is a section taken substantially on the line 5-5 in Fig. 3;

Fig. 6 is a section taken substantially on the line 6-6 in Fig. 4;

Fig. 7 is a section taken substantially on the line 7-7 in Fig. 5;

Fig. 8 is a section taken substantially on the line 8-8 in Fig. 7;

Fig. 9 is a schematic view showing the relation of certain of the can end cut-out 70 parts; and

Fig. 10 is an isolated perspective view of a can end feed cut-out, roll and mounting.

On the drawings, which illustrate an embodiment of our invention, we have shown a construction which constitutes a part of the apparatus described in our co-pending application No. 424,697, known as a horizontal stationary can double seamer for non-circular cans.

By reference to Figure 1, it will be seen that the feeding apparatus is supported from a frame 11 which extends up above the seaming mechanism, the latter being mounted on a suitable base. The operative members are encased within a casing 12 adjacent a runway 13 through which the can bodies are passed. The can ends are fed from a chute formed of guide bars 14 of angle formation, the stack of ends being supported upon a separator composed of a plurality of retractable blades 15 and separating knives or rolls 16, the blades and rolls being alternately projected into the path of the can ends by a mechanism which will 95 now be described.

Referring first to Fig. 3, it will be noted that there are three blades 15 mounted upon the end of slides 17 moved in slide ways 18 in an annular frame member 19. In the 100 frame member 19 is an annular slide groove 21 in which may be oscillated arcuately a

ring 22, which ring is provided with three inclined slots 23 into which take rolls 24 on the under surfaces of the slides 17. This ring is oscillated by an angle lever 25, pivoted at 26, on a bracket 27 on the support, and having a roll 28 taking into a cam slot 29 in a circular cam 31 upon a shaft 32. Upon this shaft is a sprocket wheel 67 which is engaged by a chain drive and given continuous rotation thereby. It will be understood that by this means the entire feeding mechanism is actuated.

Each roll 16 is carried in a swinging lever 33 pivoted at 34 in a slide block 35. This slide block normally moves with the support 15 and is held in place upon a positioning plate 36. The slide block 35 is cut away at the rear at 37 to embrace a boss 38 upon the plate 36 and on the bottom of the block 35 is a downwardly extending shoulder 39 adapted to fit in an aperture 41 on the plate 36. A recess 42 is provided in the rear of the slide block 35 and in this recess a spring 43 bearing against the boss 38 is provided. Springs 40 are positioned in recesses in the heads of the levers 33 and control vertical movement of the rolls 16. In action the rolls 16 are swung arcuately about the pivots 34 to separate the flanges of the stack of can ends, cutting out a lowermost one and permitting it to drop from the stack when the supports 15 are withdrawn. The springs 43 normally hold the slides in forward position and permit them to yield should the rolls be forced against the stack with the can ends slightly elevated and in the path of the movement of the roll edge. The spring in this event holds this roll closely against the edge of the can end and permits it to be projected in between the edge of the lowermost end and the one next above when the stack has settled sufficiently to permit this. The springs 40 also serve to make certain the release of individual ends despite unfavorable conditions. They normally hold the rolls down and prevent their cutting out more than a single end, but permit them to rise to produce separation in case they encounter a malformation of an end flange. The swinging of the levers 33 is accomplished by an annulus 44 mounted above the annulus 22, said annulus 44 being oscillated by a roll 45 carried in a bearing 46 and engaging a cam 47 upon the shaft 32. This annulus is provided with three radial slots 48 in which are disposed blocks 51 mounted upon bolts 52 taking down through slots 53 in the tails 54 of the levers 33. The bolts are adjusted in the slots engaging lock plates 55 and 56 upon opposite ends of the tails.

The can ends are thus successively cut out from the stack and fall into a directing chute 62 passing down into position in front

of the cans 65 as they reach the bottom end of the can body chute. The guiding surfaces, indicated at 63, for the ends as they come into registration with the can bodies, are so inclined with respect to each other that the shoulders of the can ends are positioned in the open ends of the bodies. They are then ready for the seaming operation of the machine below.

It will be noted that the cam 47 causes movement back and forth of the roll 16 for each rotation of the shaft 32 and that the cam 31 produces a single quick action of the slide supports. The arrangement is such that the roll moves back and forth across the can end flanges for each cut-out, and in this movement, produces separation for either on the first or second stroke. If it fails to be in position to enter on the stroke in one direction, the spring construction described permits its bodily retraction and it may enter on the return stroke. If it succeeds in passing between the flanges on the first forward stroke, the flanges remain apart so that it has no difficulty on the return stroke and positive separation is thus produced. It will also be noted that the slides 17 are movable within certain limits, being held in desired position by nuts 64, the feeding mechanism being thus adjustable both as to size and shape of the ends, by loosening the nuts 64, slightly moving the slides 17 as may be required and then re-tightening the nuts.

It is thought that the invention and many of its attendant advantages will be understood from the foregoing description, and it will be apparent that various changes may be made in the form, construction and arrangement of the parts without departing from the spirit and scope of the invention or sacrificing its material advantages, the form hereinbefore described being merely a preferred embodiment thereof.

We claim:

1. A can end feeding mechanism comprising a stack holder for holding accumulated can ends, and a plurality of retractable blades and separating knives and rolls, said blades and rolls being alternately projectable into the path of the can ends, and means for reciprocating said rolls with said plurality of strokes.

2. A can end feeding mechanism comprising a plurality of retractable blades and separating rolls alternately projectable into the path of the can ends, and, in turn, supporting and separating them.

3. A can end feeding mechanism comprising a plurality of alternately operated supporting blades and separating rolls, slides in which said blades and rolls are mounted, and cam-controlled members operating the same.

4. In a can end feeding mechanism, a plu-

- rality of separating rolls carried upon power-operated actuating members and intermittently projected into the path of the can ends to cut out and release the bottommost end of a stack. 25
5. In a can end feeding mechanism, a plurality of rolls for cutting out can ends from a stack and having a plurality of operative strokes for each operation. 30
- 10 6. In a can end feeding mechanism, a plurality of swingable separating rolls carried upon power-operated actuating members and intermittently projected into the path of the can ends to cut out and release the bottommost end of a stack, said rolls yielding either vertically or horizontally upon coming in contact with the edge of the can end and repeating their swinging movement to insure release of said bottommost end. 35
- 15 7. In a can end feeding mechanism, the combination of retractable supporting blades and separating knives and rolls alternately projectable into the path of the can ends, 40
- 20
- said blades and rolls each being operated by cam-controlled actuating members.
8. In a machine for seaming flanged can ends to flanged can bodies, a feeding mechanism comprising in combination a stack holder for holding accumulated can ends, a plurality of retractable supporting blades and separating rolls alternately projectable into the path of the can ends, separating said ends and feeding them into seaming relation with the can bodies, and means for operating said blades and rolls. 45
9. A can end feeding mechanism comprising a stack holder for holding accumulated can ends, and a plurality of retractable blades and separating knives and rolls, said blades and rolls being alternately projectable into the path of the can ends, and being adjustable both according to the size and shape of said can ends.

MAGNUS E. WIDELL.
ARTHUR A. JAHR.
